DESIGN FOR A ROTARY TOOTHBRUSH

George S. Hampe, San Francisco, Calif.

Application October 23, 1934, Serial No. 53,729

Term of patent 3½ years

To all whom it may concern:

Be it known that I, George S. Hampe, a citizen of the United States of America, residing at San Francisco, in the county of San Francisco and State of California, have invented a new, original, and ornamental Design for Rotary Toothbrushes, of which the following is a specification, reference being had to the accompanying drawing, forming a part thereof.

Fig. 1 is a front elevation of my new design,

Fig. 2 is a cross section on the line 2—2 of Fig. 1,

Fig. 3 is a cross section on the line 3—3 of Fig. 1,

Fig. 4 is an end view of the back of the brush member, and

Fig. 5 is a similar view of the front of the brush member.

I claim:

The ornamental design for a rotary toothbrush, substantially as shown.

GEORGE S. HAMPE.
